4 Claims

ABSTRACT OF THE DISCLOSURE

An apparatus for wrapping a wire or cord around the handle of a broom, mop, duster and the like and head to attach the head to the handle, having a hollow power rotated spindle for receiving the handle therethrough, a chuck at one end of the spindle for gripping the said handle, a series of pulleys for guiding a wire or cord from a storage reel to the vicinity of the rotating spindle and a number of fluid pressure actuated devices for operating a clutch between the source of power and rotating spindle and for braking the latter and for operating the spindle chuck and controlling the tension in the wire or cord.

This invention relates to a winding machine for winding a wire or cord about the handle of a broom, mop, duster and the like and more particularly to such a machine in which all the necessary operations are power actuated thus relieving the operator of the necessity of performing these operations manually, and allowing operator to work from sitting position.

In the manufacture of brooms, mops, dusters and the like, it is customary to fasten the handle to the head by winding a wire or cord around the handle and head. As the latter is made up of a great number of individual strands or bristles which must be tightly held together as a unit at the end attached to the handle to prevent their undoing, it is of prime necessity that the winding be tightly and accurately done and that all operations necessary to accomplish this be within easy and accurate control of the operator.

Applicant accordingly provides a machine which has a hollow spindle and a chuck on the spindle for gripping the handle and guide pulleys for leading the wire which is to be wrapped about the broom from a reel to the place of application of the wire to the broom. All necessary operational steps, such as application of power to the spindle to rotate the same, release of the chuck, tension of the wire or cord, etc. are within easy control of the operator and are fluid pressure actuated preferably AIA so as to relieve the operator of as much manual effort as possible in the operation of the machine.

It is one object therefore to provide such a machine which is easy to operate and requires a minimum of manual effort on the part of the operator.

It is another object to provide a machine which is simple in construction, easy to service and relatively foolproof.

It is still another object to provide a machine which may be operated by relatively unskilled persons and which requires a minimum of time to learn to operate.

Another object is to allow operator to work from a sitting position.

The above and other objects will become more apparent as this description proceeds, reference being had to the accompanying drawing, forming a part of this specification, and showing a preferred embodiment of the invention.

In said drawing:

FIGURE 1 is a front perspective view of a broom winding machine according to my invention;

FIGURE 2 is a rear elevation thereof;

2

FIGURE 3 is a detail view of the wire or cord tensioning means;

FIGURE 4 is a fragmentary view of the machine showing details of the power drive train for the spindle;

FIGURE 5 is a detail of the brake mechanism operating on the spindle, taken substantially along line 5—5 of FIGURE 4;

FIGURE 6 is a longitudinal cross-section of the chuck showing the same in gripping position;

FIGURE 7 is a view similar to FIGURE 6 showing the chuck in release position;

FIGURE 8 is a diagrammatic view of the fluid pressure circuit and operators for the various parts of the machine; and

FIGURES 9 and 10 show details of a broom in several stages of completion as it would appear on the machine as it is being wound.

Referring to the drawing in more detail, the machine consists of a cabinet 10 which houses the drive mechanism, reduction gearing and substantially the bulk of the power driven components of the device.

Projecting laterally from one side of the cabinet is a table like plate 11 which is supported at its free end on a vertical plate column 12. A foot plate 13 extends from the cabinet and also fastens to the column 12 below the plate 11 and somewhat above the level of the floor.

The drive mechanism within the cabinet 10 consists of an electric motor or equivalent prime mover 14 which drives counter shaft 15 through pulley and belt drive 16, while the counter shaft in turn drives the main spindle 17 through chain 9. The pulley and chain drives between the motor and main spindle are one of many types of drive mechanism which could be used and are shown for purposes of illustration only. Their main purpose is to provide speed reduction between the motor and main spindle and it is evident that any equivalent drive means which results in the proper speed for the main spindle may be employed.

The main spindle 17 is hollow and is adapted to receive the handle 18 of a broom therein.

Spindle 17 is mounted for rotation on bearings 17' and 17" on fixed portions of the cabinet.

One end of the hollow main spindle is provided with an actuator member 19 which is reciprocable within the spindle but is non-rotatable with respect thereto due to the screw 18' threaded into the actuator and extending through a longitudinal slot 20 in the spindle.

Surrounding the spindle adjacent the slot 20 is an outer collar 21 into which screw 18' is threaded, thus actuator 19 and the outer collar 21 are rigid with respect to each other and movement of the collar 21 along the spindle 17 will produce similar movement of the actuator 19 within the spindle.

A conical counterbore 22 is formed in one end of the actuator 19 and a contractable conical jaw or gripping member 23 is located in this counterbore.

The end of spindle 17 is provided with a cap member 24 which is threaded at 25 into spindle 17 and forms an abutment for the gripping member 23.

The actuator member 19 is normally urged toward the gripping member and cap 24 by spring 26 and thus the gripping member is normally held in contracted condition with a broom handle positioned within the gripping member and would be held thereby. The force exerted by spring 26 may be adjusted by plug 27 screwed into the opposite end of the spindle member 17 in which the plug forms an adjustable abutment for the spring.

As above stated the chuck or gripping member 23 is normally held in gripping position but is releasable for insertion or withdrawal of a broom or other handle by an air pressure piston and cylinder operator 28 pivoted be-

tween a fixed bracket 29 within the cabinet member and one end of a lever 30 pivoted to a fixed bracket 31. The other end of the lever is operatively associated with collar 21 at 32, whereby pressure applied to the closed end of the cylinder and piston will pivot the lever and shift collar 21 with associated actuator 18 to release the chuck.

The motor, or prime mover 14, is provided with a clutch (not shown) so that the machine may be stopped without stopping the motor. This clutch is actuated by a fluid pressure piston and cylinder 33 somewhat similar to operator 28 for the chuck. The piston and cylinder 33 is pivoted at one end to a bracket 34 fixed within the cabinet and pivoted at its other end 35 to a clutch operator lever 36. The piston and cylinder 33 however is double acting so as to positively engage and disengage the motor clutch (see FIG. 8).

The main spindle 17 is provided with a brake means (see FIG. 5) which will hold the spindle from rotation when applied. This brake is composed of a brake drum 37 on the spindle and a brake shoe 38 mounted on a pivoted lever 39 and actuated by cylinder and piston means 40 pivoted to the lever at 41 and to a fixed point 42 in the casing or housing. The cylinder and piston means 40 is preferable double acting (see FIG. 8) similar to piston and cylinder 33 operating the clutch, so as to positively engage or disengage the brake when so operated.

A tensioning member for the wire W is mounted on the table like plate 11 and consists of a pulley like member 43 rotatably mounted on a shaft 44 below the plate 11. Shaft 44 projects upwardly through an opening in plate 11 to a point above the plate and a spring 45 rests against plate 11 and surrounds this upwardly extending portion. A wing nut 46 is threaded on the upper end of the shaft to afford adjustment of the compression in the spring. The pulley 43 is thus urged upwardly by the spring and abuts the lower surface of plate 11 to provide a braking effect on the pulley.

A piston and cylinder operator 47 is connected at 48 to the lower end of shaft 44 and to foot plate 13 at 49 and functions to pull the shaft downwardly against the compression in spring 45 to release pulley 43 from frictional contact with the lower surface of plate 11 and thus allow pulley 43 to rotate freely on shaft 44.

Mounted on the end of cabinet 10 is a bracket member 50, while a similar bracket 51 is mounted on a plate 52 rigidly connected to the plate like pedestal 12. These brackets are mounted on bolts 53 and 54 on the cabinet and plate 52 respectively which latter bolts form pivots to allow for angular adjustment of the brackets in vertical planes. To hold the brackets in fixed adjusted positions bolts 55 and 56 through arcuate slots 57 and 58 are provided which later may be tightened.

A shaft 59 is mounted through openings 60 and 61 in brackets 50 and 51 respectively and serves as a support for guide pulley 62 mounted thereon. The series of openings 60 and 61 afford adjustment of the shaft 59 along the brackets.

A series of guide pulleys 65, 66, 67 and 68 are mounted at various points on the machine for guiding the wire or cord to be wrapped on the broom as it is fed from coil 63 supported on reel 64. The pulley 65 is located at the top corner of the cabinet and pulleys 66 at the rear of the cabinet and pulleys 67 and 68 under the plate 11.

The wire or cord from the coil 63 on the reels lead up and over pulley 65, then down to pass between pulleys 66 at the rear of the cabinet, then over pulley 67, then wrapped one or more turns around braking pulley 43, then over pulley 68, then up and over pulley 62 and finally down to a position to be wrapped around the broom.

FIGURE 8 diagrammatically illustrates the fluid pressure circuit connecting the various cylinder and piston operators previously mentioned. Fluid under pressure is admitted through the cut-off valve V to the supply line 69 which is connected to three separate valves 70, 71

and 72. The valve 70 controls the flow of fluid into the cylinder and piston operator 47 which controls the tension release on pulley 43; valve 71 controls the chuck release operator 28 on the main spindle; and valve 72 simultaneously controls the clutch release on the motor and the brake on the main spindle. This latter valve 72 and the operators connected thereto are so arranged that when operated to release the motor clutch the brake will be applied and vice versa.

10 The valves 70, 71 and 72 are located on the machine so as to be within easy access of the operator, for example, the valves 70 and 71 may be located on the foot plate 13 to be operated by the feed of the operator, while valve 72 may be located on the side of the cabinet to be accessible to the knee of the operator. Obviously any other arrangement of these valves may be had as desired, so that machine may be operated by paraplegic, blind and otherwise handicapped person.

In operating the machine the end of the wire or cord 20 W is attached to the broom handle 18 and bundles of bristles or straws 73 are positioned against the sides of the handle 18 as the spindle 17 is rotated (as shown in FIG. 9). Such bundles of straws, bristles, etc. may be positioned all around the handle so as to completely enclose the same as the winding progresses shown in FIGURE 10, and the wire wrapped about the straws or other materials and handle in the amount necessary to securely fasten the straws to the handle. All operations, such as 25 controlling the tension in the wire or cord or tightness 30 of the wrapping of the wire or cord, starting and stopping, releasing the tension, etc. are all within the easy control of the operator of the machine.

Having thus described a preferred form of the invention, it is to be understood that I do not desire to be 35 limited specifically thereto but desire to include all modifications and equivalents as fairly fall within the spirit of the invention and as defined in the appended claims.

I claim:

1. A winding machine for winding a wire or cord about 40 the handle of a broom, mop, duster and the like, comprising in combination:

- (a) a rotatable hollow spindle adapted to receive a handle element therethrough and a source of power for rotating said spindle;
- (b) a chuck means in the spindle for gripping the handle;
- (c) guide pulley means for guiding a wire to be wrapped about the handle from a source of supply to the handle gripped in the spindle chuck;
- (d) adjustable friction braking means associated with the guide pulley means for applying tension to the wire as it is being wrapped about the handle;
- (e) braking means for stopping the spindle;
- (f) air pressure means associated with the chuck for releasing the same;
- (g) means associated with the wire or cord friction guide pulley and adjustable friction means for selectively releasing the tension on the wire.

2. A winding machine for winding a wire or cord 60 about the handle of a broom, mop, duster and the like, as defined in claim 1:

- (a) said spindle chuck means having an outer tapered portion;
- (b) an actuator member in the spindle having a tapered portion cooperating with the outer tapered portion of the spindle chuck means;
- (c) a spring within the spindle acting against the operator member for urging the two tapered portions together and thus cause contraction of the spindle chuck means; and means for releasing the spindle chuck means by acting on the actuator member to move the same away from the spindle chuck means against the pressure of the spring.

3. A winding machine for winding a wire or cord about 70 the handle of a broom, mop, duster and the like as de-

fined in claim 1 in which the adjustable friction braking means associated with the cord or wire guide pulley means comprises:

- (a) a pulley;
- (b) a shaft rotatably mounting said pulley, said shaft extending thru a fixed portion of the machine;
- (c) a spring associated with the rotatable pulley bar urging the same into frictional contact with said fixed portion of the machine;
- (d) an adjustment nut threaded on the shaft and forming an adjustable abutment for the spring to vary the compression in the latter, in which the fluid pressure means for releasing the braking means acts on the shaft against the pressure of the spring to release the pulley from frictional contact with said fixed portion of the machine.

4. The structure defined in claim 1 in which said wire or cord guide pulley means comprises a series of pulleys and in which the braking means is associated with at least one of the series.
